(57) CLAIM

I claim the ornamental design for the combined bottle and cap, as shown and described.

DESCRIPTION

FIG. 1 is a perspective view of an ornamental design for a combined bottle and cap;

FIG. 2 is a first side elevational view thereof;

FIG. 3 is a second side elevational view thereof;

FIG. 4 is a third side elevational view thereof; and

FIG. 5 is a fourth side elevational view thereof.

FIG. 6 is a top plan view thereof; and,

FIG. 7 is a bottom plan view thereof.

The broken lines in the drawings depict portions of the combined bottle and cap that form no part of the claimed design.

1 Claim, 7 Drawing Sheets
